UNITED STATES PATENT OFFICE.

ANDREW J. BRADLEY, OF NEW YORK, N. Y.

PROCESS OF MAKING STEEL DIE-PUNCHES.

1,118,180.

Specification of Letters Patent. Patented Nov. 24, 1914.

Application filed July 14, 1913. Serial No. 778,889.

To all whom it may concern:

Be it known that I, ANDREW J. BRADLEY, a citizen of the United States, and a resident of the city of New York and State of New York, have invented a new and useful Improvement in Processes of Making Steel Die-Punches, of which the following is a specification.

This invention relates to steel dies and punches such as are used in stencil cutting machines, and to the art of making the same, and comprises certain improvements in the dies and processes described in my prior Patents Nos. 522953 and 613236.

Punches for stencil machines should have bodies with parallel walls exactly conforming to the shape of their faces. A punch body with parallel walls will not stretch the uncut paper surrounding the portions cut out thereby during the punching stroke, as might occur if the punch body was tapered toward the face of the punch, and also a parallel walled punch will not catch under the edges of the hole on the return stroke, as might occur if the punch body was upset or enlarged upon its face.

Dies for stencil machines should be a few thousandths of an inch larger than the faces of the punches mating therewith, and moreover, the opening through the die should be flared or slightly enlarged toward the bottom of the die in order to provide a clearance for the punched out pieces of the stencil and allow them to fall through readily.

The object of this invention is to produce interchangeable dies and punches having certain advantages hereinafter set forth.

A further object is to devise an improved process of manufacturing said dies which requires no hand filing or upsetting to insure exact conformation and proper clearance of the cutting edges.

This invention consists in the dies and punches, and in the process of making the same, hereinafter described.

No claim is made herein for the dies and punches, this part of the invention being reserved for a separate patent.

In the accompanying drawings, in which like characters are used to designate the same parts in the several views. Figure 1 is

a top plan view of the master die used in cutting the blanks from which my improved dies and punches are made; Figs. 2 and 3 are vertical sectional views of the master punch and die, respectively, on the line 2—3 in Fig. 1, looking in the direction of the arrows; Fig. 4 is a plan view of the die blank following the punching operation, showing the side which is uppermost in the punching dies; Figs. 5 and 6 are vertical transverse sections through the die blank shown in Fig. 4, on the lines 5—5 and 6—6, respectively; Fig. 7 is a top plan view of the die blank reversed to bring it into the position in which it is assembled with the punch plate; Fig. 8 is a vertical transverse section of the same on the line 8—8 in Fig. 7; Fig. 9 is a top plan view of the punch plate prior to assembling with the die blank; Fig. 10 is a vertical transverse section of the same on the line 10—10 in Fig. 9; Fig. 11 is a transverse sectional view of the punch plate superposed upon the die-blank prior to the welding operation; Fig. 12 is a view similar to Fig. 11 showing the punch plate and die-blank after the welding operation, but prior to separation of the punchings or counters from the die-blank; Figs. 13 and 14 are transverse sectional views of the welded punch plate and the die blank after separation of the counters therefrom, respectively; Fig. 15 is a bottom plan view of the finished punch; Fig. 16 is a top plan view of the finished die; and Fig. 17 is a side elevation of the finished punch and die, showing the manner in which they are mounted in a stencil cutting machine.

The drawings illustrate the master dies for shaping the die-blank and the several stages in the production therefrom of a stencil punch and die for cutting the letter G. A full set of master punches and dies, comprising all the letters of the alphabet and the usual punctuation marks and characters, together with the numeral figures 2 to 9 inclusive, is necessary to the carrying out of this process. The dies are made with the character reverse in plan view, as shown in Fig. 1, in which the master die 11 for the letter G is shown. The master dies also have three holes 12 which coöperate with pins (not shown) removably mounted in the

master punch blocks 13 for punching three justifying or dowel pin holes in the die blanks. The master dies and punches are very carefully fitted to each other, the clearance between their coöperating cutting edges being not over one one-thousandth of an inch. The side walls 14 of the openings through the master die 11 diverge slightly toward the bottom of the die to provide a clearance 5 for the punchings, or portions of the die blank which are forced through the master die by the master punches. The top portions 15 of the side walls 14 are parallel for about one thirty-second of an inch down 10 from the cutting edges thereof. The master punches 16 are tapered slightly toward the cutting edges, their side walls 17 approaching each other at the rate of about one thirty-second of an inch per inch. The 15 lower portions 18 of the side walls 17 are parallel for about one thirty-second of an inch up from their cutting edges.

The process followed in making the stencil punches and dies is as follows: A steel 25 die blank 21, about three sixteenths of an inch thick, is placed on the master die and the punch brought down until it has penetrated about four fifths through the die blank, which is sufficient to completely sever 30 the punchings 22 from the die blank, but leave them sticking therein. At the same stroke the pins in the master punch lining up with the holes 12 are forced partly through the die blank, but to a slightly less 35 extent than the punchings the lower ends of the pins being set slightly above the face of the punch. The lower ends of the posts 23 which are raised on the under face of the die blank by the pins on the punch block are 40 about one thirty-second of an inch above the lower faces of the punchings 22.

The top edges of the holes punched in the die blank are left slightly rounded by the punch instead of having absolutely square 45 corners. It is impossible to punch soft steel and get absolutely square corners on the top edges of the punched holes due to the metal surrounding the hole flowing slightly under the pressure brought upon it 50 by the punch. Heretofore, in making stencil dies by master dies having the character cut upright instead of inverted, it has been necessary to grind off the top surface of the die blank in order to get square corners for 55 the cutting edges of the stencil die made therefrom. In this process, the bottom of the die blank becomes the top of the stencil die, and the rounded corners made by the punch are of advantage in providing bottom clearance in the holes additional to that made by the tapered side walls of the punch. For a similar reason to that causing 60 the top edges of the holes to be slightly rounded, the bottom edges of the punchings

22 are slightly rounded. The punchings, 65 however, have parallel walls exactly conforming in size to the holes in the master die through which they are forced, instead of being tapered like the punch. The lower edges of the holes in the die-blank, 70 on the other hand, are slightly smaller than the holes in the master die, due to slight contraction after the withdrawal of the punch, and grip the punchings tightly.

The die-blank 21 is turned over, as shown 75 in Fig. 7, and a punch plate 24 is placed on it, with the punched out holes 25 fitting the punchings 22. The punch plate is made with the same master dies 11 and 13 with which the die blank was formed, but before punching the punch plate the punch pins are removed, and in punching the punch is forced entirely through the plate. The tapered punch bevels the side walls of the holes 25 slightly, the holes being 80 slightly wider on the side from which the punch approaches. This is the lower side of the punch plate as shown in Figs. 9 and 10. The clearance between the rounded edges of the holes in the punch plate and 85 the rounded edges of the punchings 22 is sufficient to enable the two plates to be assembled one on the other as shown in Fig. 11, but not sufficient to leave any appreciable space between the meeting corners, and 90 accordingly the punch plate serves as a templet for assisting in maintaining the proper alinement of the punchings during 95 the following operation. The posts 23 serve to position the punch plate parallel 100 with the die-blank, and insure that the depth to which the punchings project into the holes in the punch plate shall be uniform.

The punch plate and die-blank are 105 clamped in assembled position, and molten steel of the same composition as the punch plate is poured into the cavities in the latter over the punchings 22. This molten steel fuses the punchings to the punch plate and 110 forms a solid punch 26, as shown in Fig. 12. The operation is performed quickly, and the punch plate and die-blank are so massive in proportion to the molten metal that 115 they are not much distorted by heat transferred to them during the operation. Moreover, if there is slight distortion of the punch plate it does not affect the alinement of the punchings, which are securely held by both the punch plate and die-blank. After 120 the parts cool, the punch plate and punchings are separated from the die-blank, and the surplus metal from the welding operation is planed or ground off from the back of the punch plate, which 125 then appears as shown in Fig. 13.

The die-blank is placed on the master die and lined up by the pins 23. The master

punch is forced through the die-blank to trim up the cutting edges and give a slight taper or relief to the sides of the holes, and holes 27 are simultaneously punched for the 5 screws 28 which attach it to the base plate 29 of the stencil cutting machine. The edges of the die-blank are trimmed up, the screw holes 27 are counter sunk on the top side, and the die-blank is case hardened, 10 forming the finished stencil die 30, as shown in Figs. 16 and 17.

The punch plate is trimmed around its edges and drilled with two holes 31 which are counterbored on the side adjacent the 15 punches for the screws 32 which secure the punch plate to the punch block 33 of the stencil cutting machine. After mounting the punch plate, the punch is forced through the hardened stencil die, which 20 shaves off the edges of the punch walls to fit the cutting edges of the die exactly. The punch may be left soft, if only paper stencils are to be cut.

It is to be noted that the above described 25 process produces punches and dies having sharp cutting edges exactly conforming to each other without hand filing, and without grinding off the cutting faces; obviously, the punch portions coöoperating with the die 30 are exact counterparts of the holes in the latter because both are made with the same master dies. Moreover, as the dies are made from the same master dies as the punches and as a part of the operation of 35 making the punches, the process is cheaper and more rapid than processes wherein separate sets of master dies are used for shaping the punches and dies, respectively.

It is evident that the sizes, shapes and 40 thicknesses of the several parts, and the materials used, may be changed without affecting the process. It is also evident that the die-blank may be punched clear through at the first stroke of the die, and the punchings 45 reinserted therein or assembled in a separate templet for holding them properly during the operation of welding them to the punch plate. Moreover, the punchings may be secured to the punch plate by 50 welding, brazing, soldering, or any other method which will unite the parts in a secure manner.

This invention is not limited to the exact 55 number or sequence of operations described as constituting the preferred process of making my improved stencil dies.

What I claim is:

1. The process of making stencil character punches which consists in punching a 60 die-blank with a master punch conforming to a stencil character, thereby shearing punchings therefrom corresponding to said character, punching a punch plate with said master punch, inverting and partly insert-

ing the punchings from said die-blank in 65 said punch plate, and integrally securing said punchings and die plate together.

2. The process of making stencil character punches which consists in punching a 70 die-blank with a master punch conforming to a stencil character, punching a punch plate with said master punch, inverting said punch plate and inserting therein the rounded faces of the punchings from said die-blank, and securing said punchings to 75 the punch plate.

3. The process of making stencil character punches which consists in punching a 80 die-blank with a master punch conforming to a stencil character, thereby producing 85 punchings having rounded lower faces, punching a punch plate with said master punch, the upper edges of the openings in said punch plate having rounded edges, inserting said punchings in the openings in said punch plate with the rounded edges toward each other, and securing said punchings to said punch plate.

4. The process of making stencil character punches which consists in punching a 90 die-blank with a master punch conforming to a stencil character, thereby producing 95 punchings having rounded lower faces, punching a punch plate with said master punch, the upper edges of the openings in said punch plate having rounded edges, inserting said punchings in the openings in said punch plate with the rounded edges toward each other, and securing said punchings to said punch plate while holding said 100 punchings in a templet on the side opposite said punch plate.

5. The process of making stencil character punches which consists in punching a 105 die-blank with a master punch having a body which tapers toward its cutting edges, said body and cutting edges conforming in outline to a stencil character, thereby producing punchings, punching a punch plate with said master punch, inserting said 110 punchings in the wider ends of the openings in said punch plate, and securing said punchings to said punch plate.

6. The process of forming mating punches and dies for stencil characters which consists in forcing a master punch nearly through a die-blank, punching openings in a punch plate with said master punch, inserting the projecting faces of the punchings in said die-blank into the openings in 120 said punch plate, securing said punchings to said punch plate, and removing said die-blank, thereby forming sharp cutting edges on said punch and die.

7. The process of forming mating punches 125 and dies for stencil characters which consists in forcing a taper master punch nearly through a die-blank, punching openings in

a punch plate with said master punch, inserting the projecting faces of the punchings in said die-blank into the openings in said punch plate, securing said punchings to said punch plate, removing the punchings from said die-blank and forcing said master punch through it, hardening said die-blank, and forcing said punchings through said

hardened die-blank, thereby forming sharp cutting edges on said punch and die. ¹⁶

Signed at the city of New York, N. Y., this 9th day of July, 1913.
